UNITED STATES PATENT OFFICE.

WILLIAM H. NOELTING AND EMIL A. SMITHFIELD, OF EVANSVILLE, INDIANA, AS
SIGNORS TO FAULTLESS CASTER COMPANY, OF EVANSVILLE, INDIANA, A COR-
PORATION.

RIGID CASTER.

Application filed July 14, 1924. Serial No. 725,999.

To all whom it may concern:

Be it known that we, WILLIAM H. NOELTING and EMIL A. SMITHFIELD, citizens of the United States, and residents of Evansville, county of Vanderburg, and State of Indiana, have invented a certain new and useful Rigid Caster; and we do hereby declare that the following is a full, clear, and exact description thereof, reference being had to the accompanying drawings; in which like numerals refer to like parts.

This invention relates to a rigid truck type caster.

The chief object of the invention is to produce a caster which can be made from sheet metal of relatively thin gauge and so fashioned that it has greater strength than cast iron casters of considerably greater weight. The several features of the invention whereby relatively thin gauge metals may be fashioned into a caster adapted to be rigidly secured to trucks for heavy duty consists in vertically corrugating the side planes of a caster arcuately depressing the ends of the triangular shaped side flange, corrugating the base or top plate and forming the securing holds in an improved manner.

The resultant construction consists in a single sheet for relatively thin gauge metal fashioned as aforesaid to produce a caster having great strength and have economical production costs.

The full nature of the invention will be understood from the accompanying drawings and the following description and claims:

Fig. 1 is a side elevational view of what is commonly called the truck type caster. Fig. 2 is a top plan view thereof. Fig. 3 is a bottom plan view of the same. Fig. 4 is an end view. Fig. 5 is a central sectional view through an opening or securing hole and the associated parts.

In the drawings there is illustrated a top plate having a substantially circular portion 10 and two diametrically positioned fan tail or wedge shaped extensions 11. In each of the extensions 11 there is provided a pair of openings 12 and opposite openings 50 are also diametrically positioned as shown by the dotted lines in Fig. 2.

In order to secure the greatest strength the top plate or base 10 includes a circular corrugation 13 concentric with the substan-

tially circular portion 10. Concentric with 55 the corrugation 13 and substantially at a junction between the fan tail extensions and the circular portions of the base, there is formed an arcuate or curved corrugation 14. Likewise medianly positioned between the 60 openings 12 of each extension 11 is a longitudinally extending corrugation 15 and herein corrugations 15 and 14 join to form a T shaped corrugation, the base or head of which is curved and concentric with the circular reinforcing corrugation. The circular reinforcing corrugation insures against collapse of the circular portions of the base in any diametral plane. The curved corrugation 14 insures against longitudinal bending 70 of the plate along the longitudinal axis. The longitudinal corrugation insures against bending along the transverse axis at the junction between the extensions 11 and the circular portions of the base 10.

Extending downwardly from each of the elongated sides and conforming to the outline thereof is a triangular shaped side flange 16 and there is thus secured a side flange having the corrugation at each end 80 and approximately one-third in therefrom which insures against bending in a horizontal plane. The intermediate and enlarged or arched portion is not only drawn downwardly but is also drawn inwardly as shown 85 clearly in Figs. 1, 3, and 4 and thus there is produced an arching effect giving relatively greater clearance at the tread portion of the wheel 17 pivotally supported by the pin or bolt 18 in the openings 19 formed substantially at the apex of the inverted triangular frame. As shown clearly in Fig. 1 the triangular frame work adjacent this opening is formed flat as indicated by the numeral 20 to form a pair of parallel bearing plate 95 portions.

Reference will now be had to Figs. 2, 3, and 5. In said figures the openings 12 are illustrated as defined by a corrugated portion 21 immediately concentric to said opening and herein said corrugation includes the inturned portion 22 that defines said opening.

The inturned tubular portion 22 is adapted to be drawn toward the supporting member 23 by a bolt 24 to the nut 25. If the material 23 is of wood or relatively soft material the tubular portion 22 will seat itself

in said material. Furthermore the foregoing construction also acts as a lock nut for after the nut 25 has been turned up on the screw threaded bolt 24, the same is held 5 against rotation.

The side flanges 16 are fashioned so that normally they are divergent. When associated with pin 18, they are secured in substantially parallel relation in opposition to a 10 tendency to separate thereby positively insuring clearance for the wheel 17.

The invention claimed is:

1. In a caster, the combination of a supporting sheet metal base including two oppositely extending base extensions, and a pair of wheel supporting ears depending therefrom, each ear including a central bowed portion and a pair of corrugations extending substantially transverse to the base and positioned at the junction of the base with the extensions.

2. A device of the character defined by claim 1 characterized by said ears being arranged so that a plurality of planes passed

parallel to the base and successively distant therefrom respectively, each have their central portion intersections in closer proximity to each other than those of the closer plane to the base. 25

3. A device of the character defined by claim 1 characterized by the central bowed portions of the ears having their concave portions adjacent each other. 30

4. A device of the character defined by claim 1 characterized by the central bowed portions of the ears having their concave portions adjacent each other and being further characterized by said ears being arranged so that a plurality of planes passed parallel to the base and successively distant therefrom respectively each have their central portion intersections curved and in closer proximity to each other than those of the plane closer to the base. 35 40

In witness whereof, we have hereunto affixed our signatures. 45

WILLIAM H. NOELTING.
EMIL A. SMITHFIELD.
